UNITED STATES PATENT OFFICE

2,435,454

CIGARETTE PACKAGE OPENER AND
CLOSURE

Joseph Maldonado, Los Angeles, Calif.

Application January 26, 1945, Serial No. 574,689

3 Claims. (Cl. 206—41.5)

1

My invention relates to a cigarette package opener and closure, and has for its principal object, to provide a simple, practical and efficient cap like member, adapted to be readily positioned on the end of a cigarette package, said cap carrying a blade which, when the cap is applied to the package, cuts a portion of the end of the package wrapper from the body thereof, in order to render the cigarettes readily accessible and said cap also being provided with a sliding plate or cover which normally closes the opening cut in the end of the package.

With the foregoing and other objects in view, my invention consists in certain novel features of construction and arrangement of parts which will be hereinafter more fully described and claimed and illustrated in the accompanying drawings in which:

Fig. 1 is a perspective view of the combined opener and closure in open position ready to be applied to a package.

Fig. 2 is a plan view of the cap in closed position.

Fig. 3 is a longitudinal section taken on the line 3—3 of Fig. 2.

Fig. 4 is a longitudinal section similar to Fig. 3 and showing the cap on a cigarette package.

Fig. 5 is a side elevational view of the upper portion of a cigarette package with the combined opener and closure in position thereupon.

Fig. 6 is an elevational view of the upper portion of a cigarette package and showing my improved opener and closure thereupon.

Fig. 7 is a cross section taken on the line 7—7 of Fig. 2.

Fig. 8 is a cross section taken on the line 8—8 of Fig. 2.

Fig. 9 is a cross section taken on the line 9—9 of Fig. 2.

Fig. 10 is a cross section taken on the line 10—10 of Fig. 2.

Fig. 11 is a perspective view of the sliding frame which carries the cutting blade.

Fig. 12 is a fragmentary longitudinal section showing the means for limiting the outward movement of the sliding cutter carrying frame.

Referring by numerals to the accompanying drawings, which illustrate a preferred embodiment of my invention, 10 designates a plate of thin material such as metal or plastics, from one end of which depends a narrow wall 11 and walls 12 depend from the sides of said plate.

These walls 12 extend a short distance beyond the end of plate 10, opposite from end wall 11 and the lower edges of said walls 12 are turned

2

inwardly and upwardly to form narrow flanges 13, in the top of one of which is formed a shoulder 14. Extending inwardly and downwardly from the upper edges of those portions of walls 12 which project beyond the end of plate 10 are longitudinal flanges 15.

The blade carrying frame which slides on side walls 12, comprises a pair of parallel straps 16, connected at one end by a cross strap 17, with the strap 16 arranged to slide lengthwise on the inner faces of walls 12 and retained in operative positions by the flanges 13 and 15.

A stop lug 18, projects inwardly from one of the straps 16 and engages shoulder 14, to limit the outward sliding movement of the blade carrying frame.

Secured to the inner faces of straps 16 intermediate thin ends, are the ends of a horizontal plate 19, having sharpened, oppositely inclined cutting edges 20 (see Fig. 11). Struck from the central portion of plate 10 is a triangular tongue 21 which projects inwardly away from end wall 11 and which tongue is adapted to enter between the end folds of the package wrapper and thus, to a considerable extent, anchoring the cap on said package (see Fig. 4).

Formed in plate 10 near and parallel with its sides are parallel slots 22 and arranged to slide on top of said plate, is a plate 23 of thin material, such as sheet metal or plastics, which, when moved to its limit of travel away from plate 10, closes the space between the projecting ends of the side walls 12.

Closure plate 23 is held for sliding movement on plate 10, by lips or flanges 24, which depends from the sides of said plate adjacent one end and which pass through slots 22.

In order to enable closure plate 23 to be engaged when slid from one position to another, the top surface of said plate, or a portion thereof, may be ribbed or corrugated as designated by 24.

To apply the cap to a cigarette package and cut an opening therein, the blade carrying frame is withdrawn as far as possible outwardly upon walls 12 and plate 10 is now placed on top of the package and then moved inwardly thereupon, so as to engage tongue 21 between the folds of the wrapper on the end of the package, after which the blade carrying frame is slid inwardly between walls 12 so that the blade cuts through the end and side walls of the wrapper just below the top thereof.

That portion P, of the package top cut from the top may be left on as a flap cover, or it may

be torn off, thus providing an opening through which the cigarette may be readily withdrawn.

Plate 23 provides a closure for the opening cut by the blade and by pressure of the thumb or finger, may be readily shifted from one position to the other.

The cap mounted on one end of the package, provides a reinforcement for said package and counteracts tendency of same to collapse when the greater portion of the cigarettes have been withdrawn therefrom.

Thus it will be seen that I have provided a cigarette package opener and closure which is simple in structure, inexpensive of manufacture and very effective in performing the functions for which it is intended.

It will be understood that minor changes in the size, form and construction of the various parts of my improved cigarette package opener and closure, may be made and substituted for those herein shown and described without departing from the spirit of my invention, the scope of which is set forth in the appended claims.

I claim as my invention:

1. A cigarette package opener and closure comprising a pair of telescopically associated members adapted when closed to provide a cap for a cigarette package, one of which members has a pair of channel shaped side members and a top plate, which side members extend beyond the inner end of said top plate to form an opening at one end of said top plate, a member arranged for sliding movement on said top plate and adapted to close the opening therein, the other telescopic

member including parallel side straps that are arranged for sliding movement in the channel shaped side members of the other telescopic member, an end rail connecting the outer ends of said side straps and a transversely disposed blade disposed between and connected to said side strips for cutting through these portions of the end and side walls of the package that are disposed beneath the opening at the end of said top plate.

2. A cigarette package opener and closure as set forth in claim 1 with a tongue pressed downwardly from said top plate for engaging between the folded ends of the package to which said opener and closure is applied.

3. A cigarette opener and closure as set forth in claim 1, with co-operating means on one of said channel shaped side members and the side strap sliding therein for limiting the extensible movement of said telescopic members.

JOSEPH MALDONADO.
